FREQUENCY-DIVIDING SYSTEM

Harold M. Lewis, Great Neck, N. Y., assignor to
Hazeltine Corporation, a corporation of Del-
aware

Application December 13, 1938, Serial No. 245,354

9 Claims. (Cl. 250—36)

This invention relates to frequency-dividing systems for deriving from one periodic wave of a first predetermined frequency another periodic wave of a second predetermined frequency which is a submultiple of the first frequency.

Devices of this character are particularly useful in television systems where waves of various different frequencies bearing a constant frequency relation to each other are utilized. For example, it has been the practice in television transmitting systems to develop a primary timing wave the frequency of which is a common multiple of the line-scanning and field-scanning frequencies and to utilize a frequency-dividing system for deriving from the primary wave, synchronizing waves of the desired line-scanning and field-scanning frequencies. Essential features of such frequency-dividing systems are stability in operation and simplicity of construction.

It is an object of the present invention, therefore, to provide an improved frequency-dividing system embodying the essential features mentioned above.

In accordance with the present invention, there is provided a frequency-dividing system which comprises an input circuit adapted to be energized by a periodic wave of a predetermined frequency. The frequency divider also includes energy-storage means, for example, a condenser, together with means for effecting charging of the storage means only upon its discharge to a predetermined value. Discharging means are coupled to the energy-storage means and to the input circuit so as to operate only in response to, and during pulses of, the periodic-input wave, incrementally and periodically to discharge the energy-storage means at the predetermined frequency and to such an extent that a predetermined number of the incremental discharges are required to effect initiation of the charging of the energy-storage means. The discharge means may comprise a diode connected in series with the energy-storage means together with means for biasing the diode to render it normally nonconducting and means for coupling the diode to the input circuit so that the application of the periodic wave thereto periodically overcomes the bias to effect the incremental and periodic discharges of the energy-storage means. The system includes an output circuit responsive to the successive chargings of the energy-storage means. In accordance with a feature of the invention, the charging means for effectively charging the energy-storage means is effective only during that pulse from the input circuit which reduces the energy of the energy-

storage means to the extent required to effect initiation of its recharging.

For a better understanding of the present invention, together with other and further objects thereof, reference is had to the following description taken in connection with the accompanying drawing and its scope will be pointed out in the appended claims.

In the accompanying drawing, Fig. 1 is a circuit diagram, partly schematic, of a frequency-dividing system embodying the present invention while Fig. 2 is a group of wave forms representing voltages developed at different points in the system of Fig. 1 to aid in the understanding of the invention.

Referring now more particularly to the drawing, the system there illustrated comprises an impulse generator 10, a frequency-dividing system 11 and a load circuit 12, which may comprise an additional frequency-dividing system, connected in cascade as shown. The generator 10 may comprise any suitable generator or source of a periodic-impulse wave of a predetermined frequency. The system 11 comprises a voltage-dividing system constructed in accordance with the present invention, while the system 12 may be similar to the system 11 or constitute any other suitable device for utilizing the wave developed by the system 11.

Referring in detail to frequency-dividing system 11, this system comprises an input circuit including a coupling condenser 13 and voltage-divider resistor 14 connected to the output circuit of generator 10 and adapted to be energized by the periodic wave of predetermined frequency supplied by this generator. The dividing system 11 further includes energy-storage means comprising, in this embodiment, a condenser 15. Charging means are provided for effecting charging of the condenser only upon its discharge to a predetermined value, the charging means including a vacuum tube 16 having its grid-cathode circuit connected across the condenser 15 by way of a winding 17 constituting the secondary winding of a feed-back transformer. The primary winding 18 of the transformer is included in the anode circuit of the tube 16 in series with a source of operating potential, such as a battery 19. Discharging means are also provided for the condenser 15, operable only in response to, and during pulses of, the periodic input wave, for discharging the condenser 15 at the frequency of the input wave and to such extents that a predetermined number of the incremental discharges effect initiation of the charging of the energy-storage means. This discharging means comprises a uni-

laterally conductive device or diode 20 connected between the upper end of the condenser 15 and ground. The input circuit 13, 14 to the frequency divider 11 is biased by connection to an adjustable tap on the battery 19, while the diode 20 is so biased as to maintain it nonconducting by virtue of the return of the input circuit of tube 16 to an adjustable tap on voltage divider 14.

An output or buffer tube 21 is provided for the 10 dividing system 11 having its control grid and cathode connected to the corresponding elements of the tube 16 and thus, in effect, connected across the condenser 15. A series load resistor 22 is included in the anode circuit of the tube 21 and 15 anode potential for the tube is applied by way of this resistor from the battery 19. The load circuit 12 is connected across the resistor 22 by way of a coupling condenser 23. The tube 21 is biased similarly to the tube 16 so that it repeats only the 20 most positive part of the voltage impulses impressed upon its input circuit, while reversing the polarity thereof. Obviously, other output arrangements may be readily provided for the 25 dividing system 11, omitting the tube 21 which, in the embodiment shown, is useful mainly to provide an independent output circuit whereby the wave developed by the system 11 is of proper wave form as applied to the succeeding stage of the 30 system.

The operation of the system of Fig. 1 may best be explained with reference to the curves of Fig. 2 which illustrate the wave forms of the voltages developed at various points in the system. 35 Each of curves A—D, inclusive, represent voltage amplitude with respect to time. The wave developed in the output circuit of the generator 10 and appearing across the voltage-divider resistor 14, superimposed on the positive bias derived from battery 19, is illustrated by curve A, being of a predetermined frequency and preferably of substantially rectangular-impulse wave form as shown. As it will presently appear, curves B and C represent the wave forms of the voltage developed between the upper side of the condenser 15 and ground and the voltage developed between the control grid of the tube 16 and ground, respectively, while curve D represents the voltage wave developed in the output circuit of the system 11 and applied to the system 12, which, in the present case, is of a frequency one-seventh that of the 40 input wave.

Considering a cycle of operation of the system 11 as beginning at the pulse *a*, during which the condenser 15 is discharged to a maximum extent 45 and the grid voltage of tube 16 exceeds its cutoff value. Under this condition the tube 16 begins to pass current and, by virtue of the feedback windings 17 and 18, an induced positive voltage pulse *b* of curve C of large amplitude is applied to the control grid of the tube 16, causing an increase in anode current and thus a regenerative effect which drives the control grid still more highly positive so that a large grid current flows which is effective to charge the condenser 15 to its maximum negative value *c*. The decrease in the rate of change of anode current after it reaches its maximum value and the following reversal in its rate of change produces a sharp induced negative voltage pulse *d* on the control grid immediately following the regenerated positive pulse. This negative voltage pulse does not cause any grid current to flow in tube 16, so that condenser 15 is not discharged and recharged to an opposite polarity during this negative pulse. Further, the anode circuit of the 75

tube passes current only during the high positive grid pulses when the resultant grid voltage exceeds the cutoff point of the tube, as indicated in curve C. The tube 16 is thereby biased below cutoff and again becomes nonconducting. The means for charging condenser 15 is thus effective for charging the condenser only during that pulse from the impulse generator 10 which reduces the energy of condenser 15 to a value sufficient to initiate the charging cycle.

Since the diode 20 is a laterally conductive device and is biased by means of the battery 19 so that its cathode is normally positive relative to its anode, the negative charge developed on condenser 15 by the grid current of tube 16 normally cannot discharge therethrough. However, the negative pulses of the wave supplied by the generator 10 are applied to the diode, by way of the voltage-divider resistor 14 and condenser 15 so as to overcome the normal diode bias, thereby 20 rendering it conducting in response to each successive pulse of the input wave, incrementally and periodically to discharge the condenser. The amplitude of the input wave pulses, as applied to the diode 20, are so controlled by adjustment of the voltage-divider resistor 14 and adjustment of the initial diode bias by means of the adjustable tap on the battery 19, and the time constant of the discharge circuit of the condenser 15, which includes diode 20, a portion of resistor 14, and a portion of source 19, is made quite large relative to the duration of the applied pulses so that a single pulse is sufficient to effect only a predetermined partial or incremental discharge 30 of the condenser and a desired predetermined number of pulses are required to effect the discharge thereof to the value sufficient to raise the grid potential of the tube 16 above the cutoff voltage at which the tube 16 starts to pass current. For example, in the embodiment illustrated, six input pulses and consequent discharges of the condenser are insufficient to raise the grid bias to cutoff, while the seventh pulse of a cycle tends to effect a discharge similar to the six preceding discharges, but due to the fact that it 40 carries the grid bias beyond cutoff, this step is interrupted by a negative charging of the condenser the partial or incremental discharges need not be equal in amplitude.

The same voltage as is applied to the input electrodes of the tube 16 is applied to the input electrodes of the tube 21. This tube, being biased similarly to the tube 16, also passes current and repeats the input signal thereto only during the most positive pulses, so that there is developed in the output circuit of tube 21 a periodic wave comprising pulses, corresponding to the large positive grid voltage pulses, at a frequency which is a fraction, in the present case is one-seventh, of that of the input wave. The latter wave 60 is applied, as explained above, to the load circuit 12 which may operate further to divide the frequency in the same manner as the divider 11 or to utilize the wave in any other desired manner.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A frequency-dividing system comprising an

input circuit adapted to be energized by a periodic wave of a predetermined frequency, energy-storage means, charging means for effecting charging of said storage means only upon its discharge to a predetermined value, discharging means for said storage means coupled to said input circuit and operable only in response to and during pulses of said periodic wave incrementally and periodically to discharge said storage means at said predetermined frequency and to such extents that a predetermined number of said incremental discharges effect initiation of said charging of said storage means, and an output circuit responsive to the successive 15 chargings of said storage means.

2. A frequency-dividing system comprising an input circuit adapted to be energized by a periodic wave of a predetermined frequency, energy-storage means, charging means for effecting charging of said storage means only upon its discharge to a predetermined value, unilaterally conductive discharging means for said storage means, means for maintaining said discharging means normally nonconducting, means coupling said discharging means to said input circuit for rendering said discharging means conducting only in response to and during pulses of said periodic wave, incrementally and periodically to discharge said storage means at said predetermined frequency and to such extents that a predetermined number of incremental discharges effect initiation of said charging of said storage means, and an output circuit responsive to the successive 30 chargings of said storage means.

3. A frequency-dividing system comprising an input circuit adapted to be energized by a periodic wave of a predetermined frequency, energy-storage means, charging means for effecting charging of said storage means only upon its discharge to a predetermined value, unilaterally conductive discharging means for said storage means, means for maintaining said discharging means normally nonconducting, means coupling said discharging means to said input circuit for rendering said discharging means conducting only in response to and during pulses of said periodic wave, incrementally and periodically to discharge said storage means at said predetermined frequency and to such extents that a predetermined number of incremental discharges effect initiation of said charge, means for adjusting said coupling means to determine the number of said incremental discharges sufficient to initiate said charging of said storage means, and an output circuit responsive to the successive 55 chargings of said storage means.

4. A frequency-dividing system comprising an input circuit adapted to be energized by a periodic wave of a predetermined frequency, energy-storage means, charging means for effecting charging of said storage means only upon its discharge to a predetermined value, discharging means for said storage means comprising a unilaterally conductive device, means for biasing said device to maintain it normally nonconducting, means coupling said device to said input circuit for overcoming said bias and rendering said device conducting only in response to and during 70 pulses of said periodic wave, incrementally and periodically to discharge said storage means at said predetermined frequency and to such extents that a predetermined number of incremental discharges effect initiation of said charging of said storage means, and an output circuit re-

sponsive to the successive chargings of said storage means.

5. A frequency-dividing system comprising an input circuit adapted to be energized by a periodic wave of a predetermined frequency, a condenser, charging means for effecting charging of said condenser only upon its discharge to a predetermined value, discharging means for said condenser comprising a unilaterally conductive device connected in series with said condenser, 10 means for biasing said device to maintain it normally nonconducting, means coupling said device to said input circuit for overcoming said bias and rendering such device conducting only in response to and during pulses of said periodic wave, incrementally and periodically to discharge said storage means at said predetermined frequency and to such extents that a predetermined number of incremental discharges effect initiation of said charging of said storage means, and an output circuit responsive to the successive 15 chargings of said condenser.

6. A frequency-dividing system comprising an input circuit adapted to be energized by a periodic wave of a predetermined frequency, a condenser, charging means for effecting charging of said condenser only upon its discharge to a predetermined value, discharging means for said condenser comprising a diode connected in series with said condenser, means for biasing said diode 25 to render it normally nonconducting, means coupling said diode to said input circuit for the application of said periodic wave thereto for periodically overcoming said bias to discharge said condenser means incrementally at said predetermined frequency and to such extents that a predetermined number of incremental discharges effect initiation of said charging of said storage means, and an output circuit responsive to the successive 30 chargings of said condenser.

7. A frequency-dividing system comprising an input circuit adapted to be energized by a periodic wave of a predetermined frequency, a condenser, charging means for effecting charging of said condenser only upon its discharge to a predetermined value, discharging means for said condenser comprising a diode connected in series with said condenser, means for biasing said diode to render it normally nonconducting, means coupling said diode to said input circuit for the application of said periodic wave thereto for periodically overcoming said bias to discharge said condenser means incrementally at said predetermined frequency and to such extents that a predetermined number of incremental discharges effect initiation of said charge, means for adjusting said coupling means to determine the number of said incremental discharges required to effect initiation of said charging of said storage means, and an output circuit responsive to the successive 55 chargings of said condenser.

8. A frequency-dividing system comprising an input circuit adapted to be energized by a periodic wave of a predetermined frequency, a condenser, charging means for effecting charging of said condenser only upon its discharge to a predetermined value including a vacuum tube having an input circuit including said condenser and an output circuit reactively coupled to said input circuit to charge said condenser only in a negative direction, discharging means for said condenser comprising a diode connected in series with said condenser, means for biasing said diode to render it normally nonconducting, means coupling said diode to said input circuit for the ap- 70

lication of said periodic wave thereto for periodically overcoming said bias to discharge said condenser means incrementally at said predetermined frequency and to such extents that a predetermined number of incremental discharges effect initiation of said charging of said storage means, and an output circuit responsive to the successive chargings of said condenser.

9. A frequency-dividing system comprising, an input circuit adapted to be energized by a periodic wave of a predetermined frequency, energy-storage means, discharging means for said storage means coupled to said input circuit and operable

only in response to and during pulses in said periodic wave incrementally and periodically to discharge said storage means at said predetermined frequency and to such extents that a predetermined number of said incremental discharges reduces the energy stored in said energy-storage means to a predetermined value, charging means for effectively charging said storage means only during the pulse from said input circuit which reduces said energy to said predetermined value, and an output circuit responsive to successive charges of said storage means.
